DISPENSING CONTAINER

Arthur Wesley Newby, 1265 Schaumburg Road,
Elgin, Ill. 60120

Filed Nov. 4, 1970, Ser. No. 25,830

Term of patent 14 years

Int. Cl. D9—01

U.S. Cl. D9—9

FIG. 1

FIG. 4

FIG. 2

FIG. 5

FIG. 3

FIG. 6

FIG. 7

FIG. 10

FIG. 8

FIG. 11

FIG. 9

FIG. 12

FIG. 1 is an elevational view of a dispensing container showing my new design, the opposite side being a mirror image of the side shown;

FIG. 2 is an elevational view looking from the right of FIG. 1;

FIG. 3 is a top plan view thereof;

FIG. 4 is an elevational view of another embodiment of my new design, the opposite side being a mirror image of the side shown;

FIG. 5 is an elevational view looking from the right of FIG. 4;

FIG. 6 is a plan view thereof;

FIG. 7 is an elevational view of another embodiment of my new design, the opposite side being a mirror image of the side shown;

FIG. 8 is an elevational view looking from the right of FIG. 7;

FIG. 9 is a top plan view thereof;

FIG. 10 is an elevational view of another embodiment

ment of my new design, the opposite side being a mirror image of the side shown;

FIG. 11 is an elevational view looking from the right of FIG. 10; and

FIG. 12 is a top plan view thereof.

The dispensing containers are shown broken away to indicate variable length.

I claim:

The ornamental design for a dispensing container, as shown and described
